United States Patent Office

Des. 214,628
Patented July 8, 1969

214,628

AUXILIARY TELEPHONE LISTENING DEVICE

Robert D. Kahn, Rockville Centre, N.Y., assignor to
Fedtro, Inc., Rockville Centre, N.Y., a corporation of
New York

Filed Apr. 8, 1968, Ser. No. 11,354

Term of patent 14 years

Int. Cl. D14—03

U.S. Cl. D26—14

FIG. 1

FIG. 2

FIG. 5

FIG. 3

FIG. 4

FIG. 1 is a perspective view of the auxiliary telephone listening device showing the same in use;

FIG. 2 is a front elevational view of the device;

FIG. 3 is a top plan elevational view of the device;

FIG. 4 is a rear elevational view of the device; and

FIG. 5 is a side elevational view of the device.

The broken line representing the human forms are shown for illustrative purposes only.

I claim:

The ornamental design for an auxiliary telephone listening device, as shown and described.
